UNITED STATES PATENT OFFICE

HAROLD S. DAVIS, OF BELMONT, AND WALLACE J. MURRAY, OF READING, MASSACHUSETTS, ASSIGNORS, BY MESNE ASSIGNMENTS, TO PETROLEUM CHEMICAL CORPORATION, OF NEW YORK, N. Y., A CORPORATION OF DELAWARE

APPARATUS FOR FRACTIONATION OF CERTAIN HYDROCARBONS

Application filed August 5, 1926. Serial No. 127,282.

This invention relates to improved apparatus for the separation of hydrocarbon mixtures rich in olefines into fractions of predetermined characteristics and free from substantial admixture with each other.

5 The mixture treated may be derived from petroleum, peat, coal, oil shales or other carboniferous natural materials by subjecting these to controlled heating for cracking or pyrogenesis. The mixtures capable of 10 being made by appropriately heating such substances generally contain ethylene, propylene, butylenes, amylenes, hexylenes and higher olefines of the general formula C_nH_{2n} , 15 as well as diolefines, ethane, methane and hydrogen, occasionally higher paraffines and naphthenes, and certain tarry reaction products of relatively high boiling point.

This invention provides for the fractionation 20 of the efflux from cracking treatment and is particularly adapted to the treatment of the mixture resulting from a complete generation of olefine hydrocarbons as is practicable, and usually containing hydro- 25 gen, methane, very reactive highly cracked hydrocarbons such as the diolefines, isobutylene, trimethylethylene, unsymmetrical methyl-ethyl-ethylene; and other olefines such as propylene, butene-1, butene-2, pen- 30 tene-1 and pentene-2; hexylenes, and homologous olefines of a higher number of carbon atoms. Fractions containing one or more of these substances are valuable for treatment for the production of alcohols and other 35 derivatives or intermediates of derivative substances; as well as valuable in the form of group mixtures of certain boiling-point ranges as motor-fuel; and valuable for other uses for which petroleum naphthas may be 40 employed. We refer to the process invented by Harold S. Davis and Wallace J. Murray described and claimed in their application Serial No. 10,992, filed February 24, 1925, which process contemplates the fractionation 45 of such material as that upon which this apparatus is adapted to operate, for more detailed description of and claims to certain steps well adapted to be practiced by use of devices according to the present invention, 50 and for disclosure of further steps useful for

further development of the products of practice with the aid of apparatus of this invention. We refer to the process invented by Earl P. Stevenson and Clarence K. Reiman described and claimed in their application 55 Serial No. 8907, filed February 13, 1925, for a detailed description of and claims to the steps of preparing a preferred material typical of materials adapted to be treated in apparatus according to this invention.

An object of this invention is to provide effective means for the separation of certain fractions of hydrocarbons from the hot vaporous efflux of a cracking operation, for example from the vapor phase cracking of 65 petroleum, for utilization in subsequent chemical treatments for the derivation of 60 alcohols and related compounds.

A further object is to provide apparatus operating to fractionate the material treated 70 and conserve the products of cracking by their segregation into groups according to their chemical reactivity, for example toward sulfuric acid. It is desirable, for example, to separate butylene from propylene to provide 75 the most advantageous products for conversion respectively into butyl and isopropyl alcohols, as explained fully in said application Serial No. 10,992.

It is a practical observation of operation 80 in and by apparatus corresponding to this invention that the preparation of secondary alcohols with the aid of sulfuric acid absorption of olefines is advantageously to be practiced on olefines of the homologous series containing hexylenes in the substantial absence 85 of any members of the series of a higher number of carbon atoms than the hexylenes, in order to avoid the risk of polymerization of the higher members of the series. On the 90 other hand, the olefines of such higher orders are valuable constituents of motor-spirit products. The present apparatus is therefore ordinarily operated and designed especially to effect a closely cut separation into a gaseous 95 fraction containing propylene and ethylene, a fraction containing butylenes, amylenes and hexylenes, and a motor-spirit fraction containing the higher olefines.

Another object is to provide apparatus 100

adapted in the treatment of materials of the class mentioned to effect a maximum separation of hydrocarbons boiling under 225° C. from the other fractions mentioned, for the purpose of providing material capable of refining treatment to produce a motor fuel having optimum "anti-knock" properties, while recovering for further treatment a clean hydrocarbon cycle stock free from heavy carbonaceous or tarry bodies, and comprising in part any unchanged portions of the original material fed to the cracking retorts.

The preferred operation of apparatus according to this invention produces as products of the operation

(1) A gaseous fraction containing ethylene, propylene, methane and hydrogen, and substantially free from olefines more reactive and higher boiling than propylene; for example, butylene;

(2) A fraction comprising butylene, amylenes and hexylenes adapted to be maintained liquid under pressures not greatly exceeding atmospheric pressure at normal temperatures;

(3) A crude naphtha fraction of which about 90% distills off at temperatures under 225° C., and suitable after refining treatment for use as a motor fuel;

(4) A cycle stock fraction substantially boiling within the range of the original gas oil or other feed stock treated in the cracking retorts supplying material for operation of this apparatus;

(5) A fuel oil containing the tarry reaction products of cracking, if any, and other hydrocarbons unsuitable for inclusion in the cycle stock fraction.

The invention will be described as embodied in apparatus comprising a preferred species only of apparatus according to the genus of the invention. As shown in the accompanying drawings;

Fig. 1 is a flow sheet in diagram showing units of apparatus conventionally in vertical elevation and vertical section; and

Fig. 2 is a continuation of Fig. 1.

Referring now to Fig. 1, the hot efflux cracked material may flow into the apparatus at 7 preferably at a temperature near 600° C., and be received in a tarry liquid separator 1, (shown in plan) containing a baffle 7^b causing the vapors to bubble through accumulated liquid held at a constant level, and therefore adapted to pass gases and vapors through pipe 2, and deliver solids if any, and residual material condensed or collected together by a liquid shower in separator 1, through pipe 3 to cooler 4, to storage tank 5, for fuel oil and tar. Tarry liquids in the efflux 7 may be expected to be in foggy or globular distribution in the gaseous stream, and preferably their separation is facilitated by showers from branch pipes 8 of pipe 9, from a pump 10 receiving a liquid condensate through pipe

11 from a liquid separator chamber 12 in series with a primary cooler 13 (which may be any preferred kind of aerial condenser) into which pipe 2 delivers. It will be understood that cooler 13 is not relied upon to condense all of the materials of the cycle stock or motor-spirit range of boiling points or lower boiling points, but functions as a dephlegmator.

The efflux pipe 14 passes through a condenser 15, preferably water-cooled which in turn delivers to a gas-liquid separator 16, whence the liquid condensate is delivered by a pump 17 through a pipe line 20, see Fig. 2, to a certain motor spirit fractionating tower 80 90 presently mentioned. The vaporous efflux from the separator 16 may pass through a meter M adapted to indicate the rate and amount of flow of the uncondensed gases and vapors at this point in the flow produced by the vapor phase cracking system delivering through the pipe 7.

The vaporous efflux from the separator 16 is delivered through the pipe 18 to the intake side of a compressor 21, in turn delivering through pipe 22 to a cooler 23 delivering into a gas-liquid separator 24 having a liquid educt pipe 25 to a pump 19 and a vapor and gas educt pipe 26 delivering into the bottom of an absorption tower 30. Material already in a liquid state in the separator 24 is forced under pressure by pump 19 through pipe line 27, Figs. 1 and 2, which delivers the matters liquid by compression and condensation in the receiver 24 to a point in the upper part of a fractionating column, which may be of any usual bubble-plate type, for example as illustrated at 31, Fig. 2, and adapted to work at a relatively heavy gas pressure. Preferably pipe 27 delivers through a storage vessel 27^a and pump 27^b, Fig. 2.

The tower 30 is adapted and arranged to provide means for the selective absorption from the gases and vapors delivered through the pipe 26 of those constituents capable of being taken into solution in the cold in an absorbing medium such as a neutral oil of relatively high boiling point, of which the so-called "straw oil" fraction of petroleum is one useful example. Tower 30 is therefore arranged to receive for countercurrent contact between the vapor delivered through the pipe 26 and a suitable absorption oil a continuous flow of absorption oil, delivered for example by the pump 37 receiving oil from the cool absorption oil storage tank 38, Fig. 1, through the pipe 36 against a gas pressure maintained by compressor 21.

The tower 30 may have any usual bubble-plates appropriate to liquid absorption of a countercurrent of vapor or gas. In the preferred construction, the maximum temperature of the absorption oil is arranged to be controlled, and the preferred way of doing this is to provide the tower 30 with a suitable

series of refrigerating coils 40 placed in series with the educt pipe 41 and induct pipe 42 of a circulating system for a preferably gaseous refrigerating fluid, such as ammonia gas, being exhausted into a refrigerating unit 45, of any desired type, through the induct pipe 42.

The tower 30 is preferably equipped with a liquid-actuated overflow control chamber 43 of any usual or preferred type suitably controlling a valve 44 in the pipe line 46 to a pump 47 delivering by pipe 48 through one side of a heat exchanger 49, and thence delivering to a heater, shown as a pipe still 50, of any usual or suitable construction, arranged to be heated by a gas blast 51 or otherwise, and delivering through a pipe line 52 to any suitable device for stripping the absorption oil of its absorbed gases and vapors; for example a stripper column or tower of the bubble-plate rectifier type as shown at 60.

The stripping tower 60 may be aided to operate at will by steam delivered through the intake 61, and may be provided with any usual type of overflow control means in a chamber 62 operating a valve 63 in an educt pipe 64 leading to a pump 65 delivering through pipe line 66 to one side of the heat exchanger 49, and thence through cooler 67 to the cold absorption oil storage tank 38. The tower 60 may be provided with any usual overhead condenser 70 having a trapped reflux leg 71 having therein a weir 72 for delivering liquid overflow through pipe 73 and through one side of a refrigerating heat exchanger 74 which may comprise two coils 74^a and 74^b in series having a separator 74^c between them, for removal of condensed water, and thence through a gas-liquid separator 75 having a gas overflow pipe 76 leading to the intake side of the compressor 21; and therefore adapted to provide for the reflux passage of gases, or vapors still in the gaseous state, in the separator 75 through compression at 21, cooling at 23, separation at 24 and absorption treatment in the tower 30.

Liquid efflux from the receiver 75 is forced by the pump 78 through the pipe 77 into the pipe line 27 above mentioned, leading the liquids by condensation from separator 75, and by compression from separator 24, to treatment in tower 31. The refrigerating heat-exchanger 74 is suitably cooled, for example by refrigerating gas effluent from the refrigerator unit 45 through the pipe line 79, and being exhausted into the refrigerator unit through the pipe line 80.

It will be observed that so far as above described, a primary condensate of the efflux from the tube 7, consisting of high-boiling substances, has been taken out at the bottom of the separator chamber 12, and utilized as reflux liquid in the tar separator 1; and that a secondary condensate (which may be referred to as a synthetic crude) appearing at the bottom of the chamber 16 has been forced

through the line 20. This line 20 which may lead through a suitable storage vessel 20^a and pump 20^b, delivers to an appropriate place in the height of a suitable fractionating tower of the bubble-plate type shown at 90, Fig. 2, 70 from which a distillate of predetermined end-point may be taken off through the pipe 91 and cooler 92. Induct pipes into and educt pipes from fractionating tower 90 may have valved manifolds 90^a, 90^b, 90^c to provide for variation of the end-point of the distillate taken off. The liquid part of the flow from condenser 92 through sight box 93 is the fraction herein referred to as a motor spirit fraction because of the appropriate boiling 80 range of its contents, "anti-knock" and other qualifications, due to its origin and mode of fractional collection, well adapting it to use after suitable refinement alone or in mixture with other hydrocarbon substances as a 85 motor fuel. This fraction may be delivered through the pipe 94 into the crude motor spirit storage tank 95.

The residual product of operation at the bottom of the tower 90 is the cycle stock referred to above, which may be drawn off from the tower 90 by the appropriate operation of an overflow regulating means in exterior chamber 96 controlling the valve 97 in the pipe 98 leading through a cooler 99 to the 90 cycle stock storage tank 100. The residue collected in the tank 100 is material of the boiling range characteristics of the gas oil typically used as a feed stock for the cracking operation, delivering at the educt pipe 7 100 above mentioned, and, if not utilized for its chemical peculiarities, the cycle stock in the tank 100 may be returned the pipe 101 to the feed end of the cracking retort. If desired, the cycle stock material may be redistilled 105 for its contents of motor-spirit boiling range, if any, before return of the remainder to the cracking retorts.

The necessary heat input for the operation of tower 90 may be supplied by a pipe still 105 heated by the gas blast 106, or other heater, through which circulation from the bottom of the tower 90 is suitably secured, for example by the pump 107 operating in the educt pipe 108 and delivering through 110 the pipe 109. The tower 90 is preferably equipped with an overhead condenser 110 having a trapped reflux leg 111 provided with a separator and weir 112 vented through the pipe line 115 fitted with a relief valve 115^a 115 and providing a reflux gas line to the compressor 21, for the purpose of maintaining a constant maximum pressure in tower 90 and returning through the compressor 21, cooler 23, receiver 24, and absorption tower 30 so 120 much of the material as is in a gaseous or vaporous state at the weir 112. The liquid overflow at weir 112 passes through pipe line 141 and refrigerated cooler 142 to tank 140, 125 presently mentioned. 130

The gaseous overflow from the top of the tower 30 comprises the gaseous fraction above alluded to containing the propylene, the ethylene, the methane and ethane, if any, and the hydrogen, if any, effluent through the pipe 7, and resultant from efficient fractionation by the refrigerated-oil absorption in the tower 30. This gas may therefore be delivered without change, for example through the pipe 119, Figs. 1 and 2, to a gas holder for the propylene and ethylene fraction at 120.

Liquids by compression and condensation delivered through the pipe 27 to the tower 31 will also contain in solution a modicum of propylene, ethylene, etc. of the gaseous fraction to be collected in the tank 120. Therefore the pressure fractionating tower 31 is preferably arranged to include an overhead condenser 125 having a trapped reflux leg 126 provided with a gas separator 127 from which the gas overflow through the pipe line 128 is delivered through a pressure relief valve 128^a into the pipe 119 at 129.

Circulation for the operation of the tower 31 is preferably provided by a heater 130 provided with a closed steam coil 131 having valved inlets and outlets 132 and 133 respectively. Circulation pipes 134 and 135 lead to the heater 130 from the bottom and to an appropriate point of the tower 31. Liquids collecting in the bottom of the tower 31 are drawn off through an overflow regulator controlled valve 136 in the pipe 137 leading to the top of the motor-spirit fractionating tower 90, the point of entrance being controlled by manipulating valves of manifold 90^b.

The condensate flowing past the separator 40 and weir 112 and in the reflux leg 111 of the tower 90 (which, it will be observed has selectively received the higher boiling fraction from the tower 31, which in turn received the liquids from the receiver 75) comprises a closely regulated fraction preferably containing all of the available amylanes and hexylanes; these contents, under proper conditions of temperature and pressure, also holding in solution substantially all the butylenes passed through the units of the apparatus so far described, and which were taken into absorption by the refrigerated oil in the tower 30. The amylanes and hexylanes and the absorbed butylene may conveniently be delivered into the pressure tank 140. To avoid lost gases the temperature of the tank 140 is preferably kept down by refrigerating the influx, or otherwise; for example the pipe 141 delivering into the tank 140 passes through the refrigerated cooler 142 connected between the outflow pipe 79 and inflow pipe 80 for flow of the refrigerant from the refrigeration unit 45.

It will be observed that the operation of the several units of apparatus is such as to

take into absorption under pressure in tower 30 the products passing in a vaporous state the rough primary fractionation effected by the preceding condensation and compression, these products ranging to a minimum boiling point of -10° C.; that the liquids from the primary condensation at 15, 16 and from primary compression at 21, 24 are severally fractionated at appropriate pressures in towers 90 and 31; that the higher boiling through-pass from tower 31 is also fractionated at tower 90; that the several gaseous overflows from absorption at tower 30, and fractionation under pressure at tower 31, are collected together in the propylene, ethylene and other gas tank 120; and that the lower-boiling amylanes and hexylanes and butylene in solution, which were absorbed at tower 30, are received in a liquid state from tower 90 in pressure tank 140.

The apparatus thus comprises means for the segregation under pressure of hydrocarbons corresponding substantially in boiling range to the butylenes, amylanes and hexylanes from other products of vapor phase cracking. These means further comprise devices for condensation of the said hydrocarbons in two stages, severally of compression with cooling, and of absorption of condensables from residual bodies remaining gaseous under the temperature and pressure of this stage; and means for fractionation under pressure to separate the said hydrocarbons respectively from higher-boiling liquids and retained gases having liquefaction temperatures at the available pressure below a convenient temperature, e.g. -10° C. Ancillary to these effects of the apparatus, the tower 31 is a device for topping liquids by condensation and compression under continued pressure, and the tower 90 is a device for separating light, intermediate and higher fractions by bottoming out cycle stock and motor-spirit products.

In addition to the operations of the apparatus which result in collection, as mentioned, of gases of boiling points below about -10° C. (in tank 120), of materials liquid at normal temperatures under slight pressure and having an end boiling point at about 100° C. (in tank 140), operations at tower 90 result in delivery into tank 95 of crude motor-spirit having a boiling-point range of from about 100° C. to about 225° C.; and collection in tank 100 of a remainder boiling above 225° .

We claim:

1. Apparatus for separating sharp boiling point fractions from products of cracking petroleum oil, comprising a fractional condenser, a condensate outlet from said fractional condenser, a first rectifying column connected to said condensate outlet, means for taking top, bottom and side cuts from said first rectifying column, a vapor outlet from said fractional condenser, an ab-

5 sorber connected to said vapor outlet, an absorber outlet for unabsorbed hydrocarbon gases, a stripper operatively connected to strip absorbed hydrocarbons from absorption oil delivered by said absorber, a second rectifying column, a pipe delivering said stripped hydrocarbons into said second rectifying column, and means for taking top and bottom cuts from said second rectifying 10 column.

2. Apparatus for separating sharp boiling point fractions from products of cracking petroleum oil, comprising a tar separator, a tar outlet therefrom, a vapor outlet therefrom, a fractional condenser connected to said vapor outlet, a condensate outlet from said fractional condenser, a first rectifying column connected to said condensate outlet, means for taking top, bottom and side cuts 15 from said first rectifying column, a vapor outlet from said fractional condenser, an absorber connected to said vapor outlet, an absorber outlet for unabsorbed hydrocarbon gases, a stripper operatively connected to strip absorbed hydrocarbons from absorption oil delivered by said absorber, a second rectifying column a pipe connected to deliver said stripped hydrocarbons into said second rectifying column, and means for taking top 20 and bottom cuts from said second rectifying column.

3. Apparatus for separating sharp boiling point fractions from products of cracking petroleum oil, comprising a fractional condenser, a condensate outlet from said fractional condenser, a first rectifying column connected to said condensate outlet, means for taking top, bottom and side cuts from said first rectifying column, a vapor outlet 25 from said fractional condenser, a compressor connected to said vapor outlet, a separator in series with said compressor, a vapor outlet from said separator, an absorber connected to said vapor outlet, an absorber outlet for unabsorbed hydrocarbon gases, a stripper operatively connected to strip absorbed hydrocarbons from oil delivered by said absorber, a second rectifying column a pipe delivering said stripped hydrocarbons into said 30 second rectifying column, and means for taking top and bottom cuts from said second rectifying column.

4. Apparatus for separating sharp boiling point fractions from products of cracking petroleum oil, comprising a tar separator, a tar outlet therefrom, a vapor outlet therefrom, a fractional condenser connected to said vapor outlet, a condensate outlet from said fractional condenser, a rectifying column connected to said condensate outlet, means for taking top, bottom and side cuts from said first rectifying column, a vapor outlet from said fractional condenser, a compressor connected to said vapor outlet, a separator in series with said compressor, a va-

por outlet from said separator, an absorber connected to said separator vapor outlet, an absorber outlet for unabsorbed hydrocarbon gases passing said absorber, a stripper operatively connected to strip absorbed hydrocarbons from oil delivered by said absorber, a second rectifying column, a pipe connected to deliver said stripped hydrocarbons into said second rectifying column, and means for taking top and bottom cuts from said second rectifying column.
